The claim is directed to a beverage can with cap as depicted in reproductions 2.1, 3.1, and 4.1, shown in an assembled configuration whereby the cap of the claimed design is fixed on a beverage can. The front of the beverage can and cap is identical to the rear, left, and right thereof. Reproductions 2.2-2.4, 3.2-3.4, and 4.2-4.4 depict the cap portion of the claim in isolation. The broken line showing of a beverage can depicts environment and forms no part of the claimed design.
